W. R. Singleton.

UNITED STATES PATENT OFFICE.

MELVIN D. KILMER, OF NEW WINDSOR, ASSIGNOR TO THE KILMER MANUFACTURING COMPANY, OF NEWBURG, NEW YORK.

WIRE FENCE.

SPECIFICATION forming part of Letters Patent No. 406,221, dated July 2, 1889.

Application filed March 5, 1889. Serial No. 301,999. (No model.)

To all whom it may concern:

Be it known that I, MELVIN D. KILMER, a citizen of the United States, residing at New Windsor, in the county of Orange and State of New York, have invented certain new and useful Improvements in Wire Fences; and I do declare the following to be a full, clear, and exact description of the invention, such as will enable others skilled in the art to which it appertains to make and use the same, reference being had to the accompanying drawing, and to the letters and figures of reference marked thereon, which forms a part of this specification.

15 The figure represents a fence-panel containing the invention.

This invention relates to improvements in wire fences; and it consists in the construction hereinafter set forth.

20 In the annexed drawing, the letters A, B, and C represent three wires. The wires A and B are twisted together at a . The wire B passes on horizontally at b , and the wire A runs down obliquely, as at a' . At c the wire A and the wire C are twisted together, the wire A passing on horizontally, as at a^2 . The wire C runs obliquely up, as at c' , and is twisted at b' with the wire B. The wire C then passes obliquely on, as at c' , and the wire B runs obliquely down, as at b^2 , and is twisted to the wire A at a^3 . The wire B passes on horizontally as at b^3 . The wire A runs obliquely, as at a^4 , up-

ward, and is twisted to the wire C at c^3 , the wire C having passed on horizontally, as at c^2 , from the twist at b' . This is continued, the 35 wires alternately running obliquely and horizontally. This forms a light yet efficient wire fence. The wires support one another, and in case of one wire breaking the other two hold the strand up. 40

I am aware of a fence-strand made of two horizontal wires and a third wire running from one to the other, and I lay no broad claim to a fence-strand made of three wires. 45

What I claim is—

The wire fence-strand consisting of the three wires A, B, and C, the wires A and B being twisted together and the latter running horizontally and the former obliquely, the wire A being twisted to the wire C and then running 50 horizontally, the wire C running obliquely to the wire B, to which it is twisted, the wire B running from this twist obliquely to the wire A, and the wire C running horizontally, the said wires thus alternately running horizontally 55 and obliquely throughout the entire strand, as set forth.

In testimony whereof I affix my signature in presence of two witnesses.

MELVIN D. KILMER.
